UNITED STATES PATENT OFFICE.

JAMES L. HALL, OF BEAUMONT, TEXAS, ASSIGNOR OF ONE PER CENT. TO VAN O. HOLLAND, OF CLAY, TEXAS, ONE PER CENT. TO OCIE HUNT, OF SOMERVILLE, TEXAS, AND TWO PER CENT. TO EDWARD T. HALL, OF ATLANTA, GEORGIA.

CUFF-LINK.

1,350,222.

Specification of Letters Patent. Patented Aug. 17, 1920.

Application filed September 23, 1919. Serial No. 325,741.

To all whom it may concern:

Be it known that I, JAMES L. HALL, a citizen of the United States, residing at Beaumont, in the county of Jefferson and State 5 of Texas, have invented new and useful Improvements in Cuff-Links, of which the following is a specification.

The object of the invention is to provide a simple and relatively inexpensive cuff link 10 of which the elements are so related that the detachment and loss thereof, or of one of them, by reason of the disconnection of the portions engaging the button holes of the cuff, may be prevented, and at the same 15 time provide a device for the purpose indicated which may be readily applied to the cuff and which will readily lend itself to any ornamentation or settings which may be desired by the wearer.

20 Further objects and advantages will appear in the course of the following description of a preferred embodiment, it being understood that changes in form and proportion within the terms of the claim submitted, may be resorted to without departing 25 from the principles involved.

In the drawings:—

Figure 1 is a view of a cuff link embodying the invention applied in the operative 30 position to a cuff.

Fig. 2 is a side view of the link showing a cuff in section.

Essentially the cuff link consists of the head elements 10 and 11 which may be of 35 any suitable form or configuration to adapt them to lie in contact with the surfaces of the cuff and present the desired ornamental appearance, and from these head elements project arms 10^a and 11^a which are terminally connected flexibly or movably as by a 40 joint 12. In the construction illustrated the head elements consist of bars of which the

arms form extensions or continuations, said bars being outwardly curved as shown at 10^b and 11^b, at the opposite ends from the 45 joint 12 so as to conform to the shape of the cuff.

Carried by one of the head elements is a stem 13 adapted to pass through the button holes 14 of the cuff 15, said stem preferably 50 being curved concentrically with the joint 12 and carried by the other head element is a fastener or engaging means 16 which in the construction illustrated consists of a thumb nut swiveled in a bearing in the element 11 and interiorly threaded for engagement with the threaded extremity of the stem when the parts of the device are arranged in operative relation in engagement 55 with the cuff.

From the foregoing description it will be obvious that should the connection between the stem which is carried by one head element and the other head element become loosened, as frequently happens with linked buttons having detachable elements, the disconnection of the parts is prevented by the joint between the arms which extend to the meeting edges of the cuff, said flexible connection being located at a point relatively 70 remote from the stem so as not to interfere in any way with the manipulation of the device in applying it to or removing it from the cuff.

What I claim is:—

A cuff link having head elements provided respectively with an arcuate stem and a revoluble nut for engaging a threaded extremity of the stem, said elements having arms disposed radially of the stem and 80 permanently jointed in concentric relation therewith.

In testimony whereof I affix my signature.

JAMES L. HALL.
